US0D1109780S

(12) **United States Design Patent** (10) Patent No.: **US D1,109,780 S**
(45) Date of Patent: ** Jan. 20, 2026

(54) **RADIATOR COVER FOR CAR
REFRIGERATOR**

(71) Applicant: **Weijie Zhong**, Qingyuan (CN)

(72) Inventor: **Weijie Zhong**, Guangdong (CN)

(**) Term: **15 Years**

(21) Appl. No.: **35/523,335**

(22) Filed: **Nov. 29, 2024**

(80) **Hague Agreement Data**

Int. Filing Date: **Nov. 29, 2024**

Int. Reg. No.: **DM/242563**

Int. Reg. Date: **Nov. 29, 2024**

Int. Reg. Pub. Date: **Dec. 20, 2024**

(51) **LOC (15) Cl. 15-07**

(52) **U.S. Cl.**

CLAIM

The ornamental design for a radiator cover for car refrigerator as shown and described.

DESCRIPTION

1. Radiator cover for car refrigerator

1.1 : Perspective

1.2 : Front

1.3 : Back

1.4 : Left

1.5 : Right

1.6 : Top

1.7 : Bottom

1.8 : Perspective view shown in used position

The broken lines in the reproductions depict portions of the radiator cover for car refrigerator that form no part of the claimed design.

1 Claim, 8 Drawing Sheets
